(57) **CLAIM**

We claim the ornamental design for a handheld wireless device, as shown and described.

DESCRIPTION

FIG. 1 is a front top perspective view of a handheld wireless device showing our new design;

FIG. 2 is a front bottom perspective view thereof;

FIG. 3 is a back top perspective view thereof;

FIG. 4 is a front view thereof;

FIG. 5 is a back view thereof;

FIG. 6 is a right side view thereof;

FIG. 7 is a left side view thereof;

FIG. 8 is a bottom view thereof; and,

FIG. 9 is a top view thereof.
